Attorneys.

UNITED STATES PATENT OFFICE.

GRACE H. SACKET, OF RACINE, WISCONSIN.

HAT OR THE LIKE.

Application filed January 31, 1921. Serial No. 441,297.

To all whom it may concern:

Be it known that I, GRACE H. SACKET, a citizen of the United States, and resident of Racine, in the county of Racine and State 5 of Wisconsin, have invented new and useful Improvements in Hats or the like, of which the following is a description, reference being had to the accompanying drawings, which are a part of this specification.

10 This invention relates to certain new and useful improvements in hats or the like and has for one of its objects to provide a hat which may be easily and cheaply constructed in various designs and which will be 15 extremely light and comfortable to the wearer.

Another object of this invention is to provide a hat which is formed of a bendable member having cloth or other suitable material substantially concealing the same, said cloth covered member being looped into the desired shape to form the completed article.

A further object of this invention is to provide a hat structure which is formed of 25 bendable wire preferably entwined in strip materials of preferably cloth, paper or the like and then interlooped into shape, the finished article being light and capable of bending to form a hat of the desired design.

30 With the above and other objects in view which will appear as the description proceeds, my invention resides in the novel construction, combination and arrangement of parts substantially as hereinafter described and more particularly defined by the appended claim, it being understood that such changes in the precise embodiment of the hereindisclosed invention may be made as come within the scope of the claim.

40 In the accompanying drawing, I have illustrated one complete example of the physical embodiment of my invention constructed according to the best mode I have so far devised for the practical application 45 of the principles thereof, and in which:

Figure 1 is a side view of a hat embodying my invention;

Figure 2 is an enlarged detail view illustrating the manner of looping the cloth 50 covered wire forming the hat structure; and

Figure 3 is an enlarged fragmentary view illustrating the manner of threading or securing the taffeta or other suitable material on the body wire. 55

In the drawing, the numeral 5 designates a completed hat which may be in any manner shaped or formed and which is composed of a material carrying wire or other bendable material 6 interlooped in the manner hereinafter described. The wire 6 is preferably bendable but non-flexible so that the completed form may be bent into the desired shape. 60

The wire 6 is preferably threaded through 65 a strip of material 7 which may be taffeta, paper or other material and which is preferably twisted, as at 8. The wire 6 is preferably threaded through the strip of material 7, as clearly illustrated in Fig. 3, while the 70 material is preferably, although not necessarily, flat. Thereafter the material is twisted or spirally wound on the wire, the turns in the material being indicated at 8 in Fig. 3. The covered wire 6 is then interlooped from the crown and the outer loops have the free end of the wire drawn therethrough from the underside, as at 9, and then over and through the last formed loop, as at 10, and is then passed through the next 75 loop when the operation is repeated, as clearly illustrated in Figure 2. 80

From the foregoing description taken in connection with the accompanying drawing, it will be readily apparent to those skilled 85 in the art to which an invention of this character appertains, that I have provided a novel manner of constructing ladies' hats, which will produce a hat of extremely light weight, attractive in appearance, and which 90 is susceptible to ready shaping into the desired shape. The hat will readily retain its shape due to the fact that the wire 6 is preferably bendable but non-flexible. 95

What I claim as my invention is:

The method of looping a braid of material formed of a bendable member threaded through a ribbon which consists in spirally winding said braid and looping each row of braid around the next adjacent row. 100

In testimony whereof I affix my signature. GRACE H. SACKET.
